AMALIA EARLES AND EDGAR H. BARRE, OF LOS ANGELES, CALIFORNIA

ASH TRAY RECEPTACLE AND COVER

Application filed June 18, 1930. Serial No. 461,972.

This invention relates to a receptacle for waste and is especially applicable to embodiment in an ash tray.

It is an object of this invention to provide a novel receptacle wherein a cover and bowl are so arranged that the bowl is normally closed and a trough for receiving waste is provided. The bowl may be moved relative to the cover to provide an annular opening 10 at the trough bottom for dumping waste into the bowl. Thus, a normally closed bowl which will house burning and smoking waste is provided and also a trough to serve as a receptacle. There are other objects and corresponding advantages which will be apparent from the subjoined specification.

An embodiment of the invention is illustrated in the accompanying drawings, in which:—

20 Fig. 1 is an elevation of an ash tray; Fig. 2 is an axial section of the upper portion as seen on the line 2—2 of Fig. 1; and Fig. 3 is a section as seen on the line 3—3 of Fig. 2.

Referring more particularly to the drawings, an embodiment of the invention in a mobile ash tray is shown. This is merely illustrative of one embodiment of the invention, as it will be apparent that the invention may be embodied in a fixed or any suitable portable type of device. As shown, an ornate designed standard 4 is supported in upright position upon wheels 5. The standard is tubular at the upper end and is provided with diametrically opposite slots 30 6 at the upper end. Within the bore of and fixed to the standard is an abutment plug 7 upon which rests a compression spring 8.

35 At the top of the compression spring 8 is a sliding plug 10 resting on spring 8. A plug 40 9 having a tapped bore is fixed to the top of the standard 4.

A bowl 11 has a tubular guide member 12 extending axially upward so that the bowl may be mounted over the standard. Fixed to 45 the upper end of sleeve 12 are fingers 13 hav-

ing inturned tips adapted to be disposed in the slots 6 and to engage the upper end of spring 8. The plug 9 has a threaded bore to receive the threaded stem of a cover. The bowl 11 is provided with a bell shape lip 14 50 flaring outwardly from a mouth 15.

A cover of substantially conical form designated by 16 has secured thereto a threaded stem 17 with a head 18. The cover is such that it may be detachably secured in normally fixed position to the end of standard 4. With the bowl 11 slidably mounted over the standard in the position shown in Fig. 2, and the cover 16 in position, the spring 8 will urge the bowl into closed relation to the cover. 55 There is an annular trough formed by the lip and cover into which ashes, remnants of burning tobacco and other refuse may be placed. By pressing downwardly upon the bowl, it is moved away from the cover so that the 60 mouth 15 is open and such refuse contained therein will fall into the bowl. The cover is relatively positioned in expanded relation to the bowl so that it does not engage the refuse which may be in the bowl. Upon release of 65 the bowl it is moved upwardly in contracted relation to the bowl by spring 8 to closed position. Thus, the refuse may be transferred to the bowl where it is housed in a closed compartment and thus is smokeless. To empty the bowl, the cover 16 is unscrewed, and the bowl lifted from the standard 4 and emptied. It may then be replaced and cover 16 70 secured in position.

It is obvious that various mechanical 80 changes may be made without departing from the invention.

What we claim is:—

1. A receptacle for waste comprising a standard, a bowl slidably mounted on said 85 standard, a cover for said bowl normally fixed to said standard, and means urging said bowl in contracted relation against said cover.

2. A receptacle for waste comprising a standard, a bowl slidably mounted on said 90

standard, said bowl having an outflaring lip, a cover for said bowl normally fixed to said standard with its seating edge arranged for engagement with the mouth of said bowl whereby a trough is formed about said cover when in closed position, said bowl and cover being in contracted relation when closed, and a spring in the bore of said standard urging said bowl to closed position against said cover.

10 3. A receptacle for waste comprising a standard, a bowl slidably mounted on said standard, said bowl having a bell shaped lip, a cover of substantially conical form normally fixed to said standard with its seating edge arranged for engagement with the mouth of said bowl whereby to form with said bowl an annular trough when said bowl is closed, said bowl and cover being in contracted relation when closed, and means urging said bowl against said cover.

15 4. A receptacle for waste comprising a standard, a bowl slidably mounted on the upper end of said standard, a cover for said bowl detachably fixed to said standard, said bowl and cover being in contracted relation when closed, and means urging said bowl upwardly against said cover.

20 5. A receptacle for waste comprising a standard, a bowl slidably mounted on the upper end of said standard, said bowl having an outflaring lip, a cover for said bowl detachably fixed to said standard with its seating edge arranged for engagement with the mouth of said bowl whereby a trough is formed about said cover when in closed position, said bowl and cover being in contracted relation when closed, and means urging said bowl to closed position against said cover.

25 6. A receptacle for waste comprising a standard, a bowl slidably mounted on the upper end of said standard, said bowl having a bell shaped lip, a cover of substantially conical form detachably fixed to said standard with its base arranged for abutment by the mouth of said bowl whereby to form with said bowl an annular trough when said bowl is closed, said bowl and cover being in contracted relation when closed, and means urging said bowl against said cover.

30 7. A receptacle for waste comprising a standard having a tubular upper part, a bowl slidably mounted on the upper end of said standard, a cover for said bowl detachably fixed to the upper end of said standard, said bowl and cover being in contracted relation when closed, and a spring in the bore of said standard urging said bowl against said cover.

35 8. A receptacle for waste comprising a standard having a tubular upper part, a bowl slidably mounted on the upper end of said standard, said bowl having an outflaring lip, a cover for said bowl detachably fixed to the upper end of said standard with its seat-

ing edge arranged for engagement with the mouth of said bowl whereby a trough is formed about said cover when in closed position, said bowl and cover being in contracted relation when closed, and a spring in the bore of said standard urging said bowl to closed position against said cover.

70 In witness that we claim the foregoing we have hereunto subscribed our names this 9th day of June, 1930.
